United States Patent Office.

JAMES M. BAKER, OF AURORA, ILLINOIS.

Letters Patent No. 95,967, dated October 19, 1869.

STOVE-PIPE DAMPER.

The Schedule referred to in these Letters Patent and making part of the same

To all whom it may concern:

Be it known that I, JAMES M. BAKER, of Aurora, in the county of Kane, and in the State of Illinois, have invented certain new and useful Improvements in Stove-Pipe Dampers; and do hereby declare that the following is a full, clear, and exact description thereof, reference being had to the accompanying drawing, making a part of this specification, in which—

Figure 1 is a sectional front elevation of a stove-pipe, showing my improved damper in place;

Figure 2 is a vertical section of the same on the line *x x* of fig. 1; and

Figure 3 is a vertical section of the damper on the line *y y* of fig. 2.

Letters of name and kind refer to like parts in each of the figures.

The object of my invention is to furnish a simple and cheap stove-pipe damper, which may be readily adjusted to any portion of a pipe, and secured in place at any desired angle with the line of said pipe; and to this end,

It consists in the construction of the damper, and in the form and method of applying the adjustable pivot, and further, in the employment of a toothed segment, with which a crank, secured to and forming a part of said adjustable pivot, is made to engage, and, in connection therewith, in the employment of an inclined slot within which said pivot rests, as is herein-after fully set forth.

In the annexed drawing—

A represents the stove-pipe, having pivoted therein a damper *B*, provided with a permanent and an adjustable pivot, *C* and *D*, respectively.

The adjustable pivot *D* is enlarged; and flattened from the point where it enters the damper *B*, the latter of which has three or more transverse cuts, somewhat longer than the width of the enlarged portion of the pivot, between which the sections of metal *b* are corrugated or bent outward, alternately, in opposite directions, so as to permit said enlarged portion *d* to pass between.

In order to permit the damper to be placed within the pipe, two holes, for the reception of the pivots *C* and *D*, are provided in opposite sides of said pipe, one of said holes being round, while the other is elongated, so as to permit of the passage of the enlarged or flattened portion *d* of the pivot *D*.

If now the disk *B* be placed within the pipe, the pivot *C* inserted in the round hole, and said disk held in position, the flattened end of the pivot *D* may be readily passed through the elongated opening in said pipe and inserted in place within the disk.

Secured to the side of the pipe, directly beneath the adjustable pivot *D*, is a metal strip, *E*, which extends upward, outward, and again upward, as shown in fig. 2.

The upper part of this strip is extended to one side in the form of a quadrant, *E'*, and has upon the semi-circular portion thereof, a series of notches, *e*, which receive the horizontal portion of a crank-handle, *F*, secured to and forming a part of the pivot *D*.

The pivot *D* extends through the pipe into the strip *E*, and rests in the lower end of a slot, *G*, which inclines upward at an angle of forty-five degrees or thereabouts.

The opening in the pipe being correspondingly elongated, it will be seen that the pivot *D* and the front end of the damper can be raised, so as to release the handle *F* from engagement with the teeth of the quadrant, and permit said damper to be adjusted to the desired angle with reference to the pipe, after which, upon releasing said handle, the pivot and damper return to their former position, and the handle is again caused to engage with the quadrant, firmly locking said damper in place.

As thus constructed, the device consists of three pieces only, the damper, the adjustable pivot and handle combined, and the lock strip, all of which may be cast, so as to require no fitting up, and as the whole can be applied to or removed from a pipe in a few minutes, it is believed that the damper can be furnished at a cost not exceeding those of ordinary construction.

The advantages possessed by a damper, which, while readily adjusted to any desired position, is at other times immovable, are so obvious as not to require enumeration, and when to these qualities is added that of cheapness, it is believed that its general use is certain.

Having thus fully set forth the nature and merits of my improvement,

What I claim as new, and desire to secure by Letters Patent, is—

The disk *B*, provided with the corrugated sections *b* and with the fixed pivot *C*, in combination with the removable pivot *D*, provided with the enlarged and flattened portion *d*, substantially as and for the purpose specified.

Also, the means employed for adjusting the damper to and securing it in position, consisting of the quadrant *E*, provided with the notches *e*, and with the inclined slot *G*, and the pivot *D*, provided with the crank-handle *F*, all constructed and arranged substantially as and for the purpose set forth.

In testimony that I claim the foregoing, I have hereunto set my hand, this 10th day of September, 1869.

JAS. M. BAKER.
